[57] CLAIM

The ornamental design for a telephone for automobiles, substantially as shown.

DESCRIPTION

FIG. 1 is a perspective view of a telephone for automobiles showing my new design;

FIG. 2 is a perspective view with the handset removed from the telephone base;

FIG. 3 is a front elevational view of FIG. 1;

FIG. 4 is a rear elevational view thereof;

FIG. 5 is a top plan view thereof;

FIG. 6 is a left side elevational view thereof;

FIG. 7 is a right side elevational view thereof; and

FIG. 8 is a top plan view with a handset removed from the telephone base, numerals being displayed on an upper section of a telephone base panel during a turn-on time.
